UNITED STATES PATENT OFFICE.

LEON JONATHAN SLIFER, OF STERLING, KANSAS.

LOADING MACHINE.

1,244,381.

Specification of Letters Patent. Patented Oct. 23, 1917.

Application filed June 5, 1917. Serial No. 172,968.

To all whom it may concern:

Be it known that I, LEON JONATHAN SLIFER, a citizen of the United States, and a resident of Sterling, in the county of Rice 5 and State of Kansas, have invented new and useful Improvements in Loading Machines, of which the following is a specification:

My invention is an improvement in loading machines, and has for its object to provide a machine of the character specified, by means of which dirt, sand, gravel and the like may be loaded directly from a slip or scraper to a wagon, the slip or scraper 10 dumping directly on to the loading table, and lifting the loading table by the further movement of the said scraper.

In the drawings:

Figure 1 is a perspective view of the improved machine;

Fig. 2 is a detail showing the manner of supporting the frame for transportation;

Fig. 3 is a longitudinal vertical section;

Fig. 4 is a section on the line 4—4 of Fig. 25 3, looking in the direction of the arrows adjacent to the line;

Fig. 5 is a transverse section through the loading table;

Figs. 6 and 7 are sections on the lines 30 6—6 and 7—7 of Fig. 5, each view looking in the direction of the arrows adjacent to the line; and

Fig. 8 is a partial perspective view, looking at the opposite side from Fig. 1.

In the present embodiment of the invention, a suitable frame is provided, consisting of longitudinally extending bars 1, parallel and spaced apart from each other, and of angle material, the said bars having a horizontal and a vertical portion, the horizontal portion resting upon the ground, as shown, when the device is in use.

A rail 2 is connected to each bar 1, the said rails being of channel material and being arranged in inclined position, as shown, and the rails are supported at the ends of the bars 1 by vertical bars 3, and they are connected by bars 4 and 5. The uprights 3 are also connected by inclined bars 6. Each 40 of the rails 2 is provided intermediate its ends, with an oblique portion 8, the said portions being parallel with the bars 1, and the channels of those portions of the rails below the oblique portions 8 are continuous with 55 the channels of the oblique portions.

A loading table 9 is provided for loading

the material, the said table having an extension or apron 10 at one end, the apron having journaled thereon wheels 11 which are designed to run in the channels of the 60 rails. The apron or extension is braced against the table by inclined braces 12, and a shaft 13 is arranged transversely of the table at the apron, and between the table and the braces. This shaft has flanged 65 wheels 14 at its ends, which run upon the top sides of the rails 2, the flanges engaging inside the rails. Clips 15 are journaled on the ends of the shaft, and these clips are connected with hoisting cables to be later described.

The hoisting mechanism consists of flexible members 16, as, for instance, cords or cables, and the said cables are connected at one end with the clips. The other end of 75 each cable passes upwardly over a reel 17 at the adjacent end of the shaft 18, which is journaled in bearings 19 at the upper ends and on the inner faces of the rails 2. From the reels, after a few turns thereon, the 80 cables 16 pass downwardly over a pulley 20 on the outer face of the adjacent extension 8, and beneath a pulley 21 on the adjacent end of a receptacle 22. These pulleys 20 and 21 are held between brackets 23 and 85 the extension and the receptacle, respectively, and the ends of the cord remote from the clips 15 are connected with the outer face of the extensions 8, as indicated at 24.

It will be evident that when the shaft 18 90 is turned in the proper direction to wind up that portion of the cord 16 between the clips 15 and the reel, the table will be lifted, running up the inclined rails, while the receptacle 22 will be lowered. This receptacle 95 may be filled with sand or the like, and the said receptacle is a counter-weight.

A reel 25 is secured to one end of the shaft 18, the said shaft being extended for this purpose, and one end of a flexible member 26 100 is secured to the reel and winds thereon. The other end of the flexible member passes downwardly beneath a pulley 27 on the adjacent rail 2, and around another pulley 28 on the adjacent bar 1, and to a connection 105 with a mechanism for engagement by the doubletree of the scraper team to raise the load. The said mechanism comprises a catch plate 29 which is mounted to slide upon an eye rail 30 arranged perpendicular to the adjacent bar 1, and extending laterally outward from the said bar. This catch plate 110

is adapted to be engaged by the doubletrees 31 of the scraper team when the said doubletrees are lowered after the dumping of the scraper, to move the said catch plate outwardly, to raise the loading table.

Releasing mechanism is provided for releasing the doubletree from the catch plate. The said mechanism comprises a shoe 32 which is mounted to slide on the rail 30 and 10 is pinned thereto by means of a pin 33. The shoe 32 carries a pair of cam members 34 substantially V-shaped, and connected to the shoe in substantially inverted V-shape, and supported in such manner that they will 15 lift the doubletree out of engagement with the catch plate, as indicated in dotted lines in Fig. 5.

In operation, with the parts in the position of Fig. 1, that is, with the table in receiving position, the slip or scraper is driven transversely of the table toward the element 29, and as the scraper reaches the table it is dumped, the load falling upon the table. The doubletree is lowered by the dumping 25 of the scraper and engages the element 29, and as the horses move ahead the table is lifted, moving upwardly horizontally until the wheels 11 enter the horizontal portions 8 of the track. A continued movement of 30 the table dumps the load, as indicated in Fig. 3, into the wagon, the load sliding down into the wagon which is arranged beneath the high ends of the rails. The load passes down the apron or extension 10 into the 35 wagon.

As soon as the doubletree engages the cam bars 34 the doubletree is lifted out of engagement with the element 29, and the table returns by gravity to receiving position. 40 The table is heavier than the counter-weight in order that it may return of its own accord to receiving position. In order to permit the machine to be transported, a pair of wheels 35 is provided, the said wheels being

on the ends of an axle 36. The bars 1 are 45 provided with hooks 37 pivotally connected with the bars for engaging the axle, and to connect the frame with the axle it is only necessary to lift the same until the hooks can be engaged with the axle. 50

It will be noted from an inspection of Fig. 1 that a rod 38 is arranged transversely of that end of the frame remote from the counter-weight, the said rod being held by arms 41 extending longitudinally from the 55 bars 1. Draft apparatus may be connected with this rod, as, for instance, chains to connect with a draft animal.

I claim:

1. A device of the character specified comprising a loading table, an incline upon which the table is mounted to run and having means in connection therewith and in connection with the table for dumping the table when it is hoisted, a catch plate having 60 guided movement toward and from the table and controlling the operation of the hoisting mechanism and adapted for engagement by the unloaded scraper to operate the same, and means for releasing the catch 65 plate when the table has been dumped.

2. A device of the character specified, comprising a loading table, inclined track rails for the table, said table having wheels running on the track rails and said track rails 75 having guide channels, said guide channels diverging horizontally from the rails intermediate the ends of the rails, the table having an extension provided with wheels engaging the channels to cause the table to 80 dump when the extension wheels run into the horizontal portions of the channels, and means for raising the table.

LEON JONATHAN SLIFER.
